Term of patent 7 years

Int. Cl. D6—01

U.S. Cl. D33—7

FIG. 1 is a front elevational view of a computer programmer's desk embodying my new design;

FIG. 2 is a perspective view thereof as viewed from above and from the right in FIG. 1, the left end being a mirror image of the right end, the pull-out leaf being shown extended and the easel thereon shown as raised; and

FIG. 3 is a rear elevational view thereof.

I claim:

The ornamental design for a computer programmer's desk, substantially as shown and described.
